Fitter.

UNITED STATES PATENT OFFICE

2,046,170

SHOE LENGTHENING DEVICE

Dominick Korytar, Chicago, Ill.

Application November 24, 1934, Serial No. 754,604

10 Claims. (Cl. 12—123.6)

The invention relates to a novel and improved device for stretching shoes or the like, and more particularly to a device adapted for stretching shoes lengthwise, whereby the length of the same may be increased.

Devices heretofore commonly employed for this purpose include expandable means disposed within the shoe, which means were then acted upon to stretch the shoe, said means acting against the forward end of the shoe and the heel portion thereof. The result of this form of stretching was not a lengthening of the shoe, but a stretching of the side upper edges thereof causing in many instances a breaking along said edges with resultant bulging at the side edges when the shoe is again placed on the foot of the wearer.

It is an object of this invention to overcome the above difficulties by the provision of a device particularly adapted for lengthening shoes, the stretching operation of which will be accomplished without the exertion of any pressure against the heel portion of the shoe.

Another object of the invention is to provide a device of the character described adapted for disposition in the forward end of a shoe for stretching the same lengthwise, including a yoke member disposed on the outer forward end of the shoe and against which the reaction of the stretching operation takes place.

Another object of the invention is to provide a device of the character described including an adjustable member disposed in the forward end of the shoe, and means for forcing said adjustable member against said forward end of the shoe and a yoke disposed on the outer forward end of the shoe cooperating with said first mentioned member for permitting a lengthening of the shoe without the exertion of pressure on the rear portion of said shoe.

A further object of this invention is to provide a device of the character described particularly adapted for lengthening shoes which may be simple in construction, assembly and operation, and which may be produced along lines convenient for cheap manufacture, but which will at the same time be highly efficient for carrying out the purposes for which it is designed.

With the foregoing and other objects in view, which will appear as the description proceeds, the invention consists in certain novel features of construction, arrangement and combination of parts, hereinafter more fully described, illustrated in the accompanying drawings, and particularly pointed out in the appended claims, it being understood that various changes in the

form, proportion, size and minor details of the structure may be made without departing from the spirit or sacrificing any of the advantages of the invention.

For the purpose of facilitating an understanding of my invention, I have illustrated in the accompanying drawings a preferred embodiment thereof, from an inspection of which when considered in connection with the following description, my invention, its mode of construction, assembly and operation, and many of its advantages should be readily understood and appreciated.

Referring to the drawings in which the same characters of reference are employed to indicate corresponding or similar parts throughout the several figures of the drawings:

Figure 1 is a view in perspective of a device embodying my invention, the same being shown disposed in operative position within a shoe;

Fig. 2 is a side elevational view of the same removed from the shoe;

Fig. 3 is a longitudinal sectional view through the same taken substantially on line 3—3 of Fig. 4;

Fig. 4 is a front elevational view of the same;

Fig. 5 is a transverse sectional view taken substantially on line 5—5 of Fig. 3;

Fig. 6 is a sectional view taken substantially on line 6—6 of Fig. 3;

Fig. 7 is a sectional view taken substantially on line 7—7 of Fig. 3; and

Fig. 8 is a sectional view taken on line 8—8 of Fig. 3.

Stated generally, the invention comprises a device which is particularly adapted for stretching the forward portions of shoes or the like without stretching the side edges thereof, this being accomplished by the elimination of any pressure during the stretching operation on the heel portion of the shoe. In the embodiments illustrated, the invention includes a member 10 made of suitable metal, said member being provided with a sole portion 11 which is shaped substantially in the form to adapt it for disposition on the inner face of the sole of a shoe, said member 10 being provided with a rearwardly inclined portion 12.

The side portions of said member 10 are bent upwardly, as shown at 13, and the free edges of said upwardly extending portions are then bent inwardly as shown at 14 for a purpose to be presently more fully described. Similarly the inclined portion 12 has the side edges thereof bent upwardly and then inwardly to form a socket 15 for a purpose to be presently more fully described.

Pivots secured to the forward portion of the member 10 is a member 16, said member being also formed of metal and being shaped to engage against the inner edge of the vamp of the shoe. This member 16 is provided at its forward portion with the depending side ears 17, by means of which ears said member is pivotally secured by means of the rivet 18 to the upstanding side edges 13 of the member 10. The member 16 is provided with a rearward extension 19 in the upper face of which is formed an elongated slot 20, said slot being open at its free end and is in communication with a guide recess 21 provided in the extension 19.

The rearwardly extending socket 15 of the member 10 is adapted for receiving therein an extension 22 of a substantially vertically disposed yoke member 23, said member being shaped substantially as shown in the drawings and is provided with the top wall 24 through which is threaded a screw member 25, on the lower end of which is mounted the member 26, said member being adapted for disposition within the recess or guide 21, as shown in Fig. 6, with the body of the screw member 25 extending through the slot 20. The member 26 is freely rotatable on a reduced portion on the lower edge of the screw member 25 to permit free rotation of the screw 25, which rotation will impart the desired movement to the member 16 for lowering or raising the same about its pivots 17. As shown in Fig. 6, the member 26 will slide within its guide slot 21 during the last mentioned operation.

A suitable handle 27 is provided at the upper portion of the screw 25 for facilitating in the actuating of the same. By reason of the means just described the member 16 may be adjusted within the shoe to the desired position relative to the member 10.

Pivots mounted between the side walls of the member 23 adjacent the lower portion thereof, is a block member 28, said block member being pivotally secured to said side walls of the member 23 by means of the rivets 29, and said block member is provided with a threaded opening extending at an inclined angle therethrough, within which opening is received in threaded engagement the screw member 30, said screw member extending through an enlarged opening 31 in the rear wall of the member 23 and having its lower portion provided with a semi-cylindrical head 32 rigidly secured thereto for a purpose to be presently more fully described. The upper free end of the screw member 30 is provided with a screw handle 33 for facilitating the actuation of the same.

Mounted within the forward portion of the member 10 is a member 34, said member being formed of suitable cast metal and is provided with suitable slots 35 on each side thereof, which slots are adapted to receive the inwardly extending flanges 14 of the member 11, whereby said member 34 will ride upon said flanges in its back and forth movement relative to the forward edges of the members 10 and 16. Adjacent the rear portion of the member 34 is provided a semi-cylindrical recess 36 within which is adapted to be received the semi-cylindrical head 32 of the member 30, whereby the operation of the member 30 in a clockwise direction will exert pressure on the member 34 to force the same forward, in which forward movement said member will be guided upon the flanges 14.

The forward portion of the member 34 is provided with a screw threaded stud 37 upon which

is threaded a toe piece 38 made of suitable material, which toe pieces may be made of various sizes and detachably secured to the member 34 in the manner illustrated.

By reason of the mechanism so far described, it will be readily apparent that the member 16 may be adjusted by the actuation of the screw member 25 to the desired position relative to the member 10, and that the actuation of the member 34 may be accomplished by the rotation of the screw member 30 in the desired rotation. This mechanism may be disposed within the forward portion of a shoe and the members 25 and 30 actuated to move the same in proper position within the shoe prior to starting the actual lengthening operation.

The following mechanism is provided for taking up the rearward pressure exerted on the member 34 by means of the screw 30. This mechanism includes a cross piece 39 rigidly secured to the rear wall of the member 23 at a point immediately above the screw member 30.

A suitable yoke 40 of substantially inverted U-shaped formation is provided, the lowermost portions of said arms of the yoke 40 being threaded as shown at 41, said portions being adapted for receiving therein a cross plate 42, the major portion of which is covered with a suitable covering 43 of rubber or leather. The cross plate is secured in place on the yoke member 40 by means of the wing nuts 44 threaded on the threaded portions 41 of the legs of the yoke 40.

Rigidly secured to the yoke 40 are the rearwardly extending side arms 45 to the forward ends of which are pivotally secured, as shown at 46, rearwardly extending arms 47. The lower edges of said arms 47 are provided with a plurality of notches 48, which notches are adapted to engage the cross bar 39 as shown in Figs. 1 and 2 of the drawings. By providing a plurality of said notches 48 the position of the yoke 40 with reference to the member 23 may be readily adjusted. A suitable flexible covering 49 may also be provided for the top portion of the yoke 40 to prevent marring or injury to the shoe when the device is in operative position thereon.

In operation, the device with the yoke 40 removed therefrom is disposed within the shoe to be operated upon, a toe piece 38 of suitable size having first been selected and attached to the member 34. The screw member 25 is then actuated to bring the vamp piece or member 16 into proper position with reference to the vamp of the shoe.

The yoke 40 is then placed in position on the outer portion of the shoe, as shown in Fig. 1, and the wing nuts 44 actuated to bring the cross piece 43 to bear against the sole portion of the shoe. The arms 47 are then swung into engagement with the cross bar 39, one of said notches 48 on the underside of said arms 47 engaging said cross bar. The lengthening operation may now be accomplished by actuating the screw member 30 by means of the handle 33, which actuation will force the toe piece 38 forwardly into the forward portion of the shoe, the rear pressure being taken up by the yoke 40 through the arms 47 and cross bar 39. It will be noted that the yoke will bear against the vamp portion 16 of the device, thereby clearly eliminating any stretching or the exertion of pressure on the side edges of the shoe.

From the above it should be readily apparent that I have provided a device which will be highly efficient for lengthening a shoe while at the same time preventing stretching or injury to the

side edges thereof. In assembled position, the device will conform to the inner configuration of the vamp portion of the shoe with the toe section disposed in position for longitudinal movement only. By providing the guide flanges 14 upon which the toe section is slidably mounted, it will be noted that the said toe section will move in a substantially horizontal plane when urged forwardly by the actuation of the screw member 30. It will also be noted that by reason of the adjustable engagement of the toe piece 38 with the sectional member 34, toe pieces of varying sizes may be employed. The adjustability of the vamp portion 16 will permit the use of the device on shoes of varying sizes and varying styles. Similarly the provision of the plurality of notches on the arms 41 will enable the device to be adjusted to accommodate it for use upon shoes of various sizes and lengths. It is believed that my invention, its mode of construction, assembly and operation, and many of its advantages should be readily understood from the foregoing without further description, and should also be manifest that while a preferred embodiment of the invention has been shown and described for illustrative purposes, the structural details are, nevertheless, capable of wide variation within the purview of my invention as defined in the appended claims.

What I claim and desire to secure by Letters Patent of the United States is:

1. A device of the character described comprising a pair of pivotally secured members adapted to conform to the interior configuration of the vamp portion of a shoe, a toe section slidably mounted within the forward portion of said members, an upright associated with one of said members, a nut carried by said upright, an adjusting screw threaded in said nut, the forward end of said screw being adapted for engagement with the toe section for forcing the latter forwardly, a yoke adapted for disposition around the outside of the shoe at the vamp portion thereof, rearwardly extending arms pivotally secured to said yoke, and means carried by said upright for engagement with said arms.

2. A device of the character described comprising a member adapted for disposition along the sole portion of the vamp of a shoe, a second member pivotally secured thereto at its forward end, said two members being adapted to conform to the interior configuration of the vamp portion of a shoe, a toe section slidably connected within said first mentioned member, said toe section having a recess provided with a semi-cylindrical bearing surface opening through its rear face, an upright associated with said first mentioned member and having a screw threaded through the top wall thereof for slidable engagement with said second member, whereby the elevation of said second member may be adjusted, a nut secured within said upright, an adjusting screw threaded in said nut with the forward end of said screw having a semi-cylindrical head adapted for disposition within the recess in said toe section, whereby the actuation of said screw will force said toe section forwardly, a yoke mounted on the outside of said shoe adjacent the vamp portion thereof having rearwardly extending arms pivotally secured thereto, and means provided on said upright for engagement with said arms.

3. A device of the character described comprising a pair of members pivotally secured at their forward ends and being adapted to conform to the interior configuration of the vamp portion of

a shoe, a toe section slidably mounted within the forward portion of said members, said toe section being capable of longitudinal movement only, an upright connected to one of said members adjacent the rear portion thereof, a nut connected within said upright, a screw threaded in said nut and having its forward end in engagement with the toe section for forcing the latter forwardly, and a yoke member disposed around the outside of the shoe having rearwardly extending arms pivotally secured thereto in engagement with said upright. 5

4. A device of the character described comprising a pair of members pivotally secured at the forward ends adapted to conform to the interior configuration of the vamp portion of a shoe, a toe section slidably mounted in the forward portion of said members, means for adjusting said members relative to each other, an upright associated with one of said members adjacent the rear portion thereof, a nut carried by said upright, a screw member threaded in said nut and disposed in position for engaging the rear face of said toe section for forcing the latter forwardly, a yoke surrounding the outside of the shoe adjacent the vamp portion thereof having rearwardly extending arms pivotally secured thereto, the free ends of which are adapted for detachable engagement with a fixed portion on said upright. 20

5. A device of the character described comprising a pair of members pivotally secured at the forward ends adapted to conform to the interior configuration of the vamp portion of a shoe, a toe section associated with the forward portion of said members and being arranged for longitudinal movement relative thereto, an upright connected with one of said members adjacent the rear portion thereof, a nut fixedly secured within said upright, a screw threaded on said nut and adapted for engaging the rear face of said toe section for 35 forcing the latter forwardly, a second screw threaded within said upright and connected with one of said first mentioned members for adjusting the elevation thereof relative to the other of said members, a yoke disposed around the outside 40 of the shoe adjacent the vamp portion thereof having rearwardly extending arms pivotally secured thereto, the free ends of which are detachably connected with a fixed portion of said upright, and means for detachably securing said 45 yoke in operative position on the shoe. 50

6. A shoe lengthening device comprising co-operating members adapted when in operative position within a shoe to conform to the interior configuration of the vamp portion of the shoe, 55 said members including a longitudinal movable toe section, means for applying pressure to said toe section for forcing the same forwardly, and means disposed on the outside of the shoe connected with said members adapted for taking up 60 the reaction of the pressure applied to the toe section during the lengthening operation, said means including a yoke and a pair of arms extending rearwardly from said yoke and connecting same with said members. 65

7. A shoe lengthening device comprising a pair of adjustable co-operating members adapted for disposition within the vamp portion of a shoe and to be adjusted to conform to the interior configuration of the vamp portion of a shoe, a toe section carried by said members and longitudinally movable relative thereto, means for applying pressure to said toe section for forcing the same forwardly, and means disposed on the outside of the shoe and connected with said members adapt- 70 75

ed for taking up the reaction of the pressure applied to said toe section during the lengthening operation, said means including a yoke and a pair of arms extending rearwardly from said yoke, the free ends of said arms being adjustably connected with said members.

8. A shoe lengthening device comprising a pair of members pivotally secured at their forward ends and adapted when disposed in the vamp portion of a shoe to be adjusted to conform to the interior configuration of said vamp portion, a toe section associated with said members and adapted for longitudinal movement, means associated with said members for applying pressure to said toe section for forcing the same forwardly, and means disposed on the outside of said shoe and connected with said members adapted for taking up the reaction of the pressure applied to the toe section during the stretching operation, said means including a yoke, and a pair of arms pivotally secured to said yoke and extending rearwardly therefrom, the free ends of said arms being adapted for adjustable connection with said members.

9. A shoe lengthening device comprising a pair of members pivotally secured at their forward ends and adapted when disposed in the vamp portion of a shoe to be adjusted to conform to the interior configuration of said vamp portion, a toe section associated with said members and adapted for longitudinal movement, means associated with said members for applying pressure to said toe

section for forcing the same forwardly, and means disposed on the outside of said shoe and connected with said members adapted for taking up the reaction of the pressure applied to the toe section during the stretching operation, said last mentioned means including an adjustable yoke removably arranged on the outside of the shoe, and having a pair of arms extending rearwardly therefrom, said arms being pivotally secured to said yoke and the free ends thereof being adapted for adjustable connection with said members.

10. A shoe lengthening device comprising a pair of members pivotally secured at their forward ends and adapted when disposed in the vamp portion of a shoe to be adjusted to conform to the interior configuration of said vamp portion, a toe section associated with said members and adapted for longitudinal movement, means associated with said members for applying pressure to said toe section for forcing the same forwardly, and means disposed on the outside of said shoe and connected with said members adapted for taking up the reaction of the pressure applied to the toe section during the stretching operation, said last mentioned means including an adjustable yoke removably arranged on the outside of the shoe, the connection therefor to said members being adjustable and including a pair of rearwardly extending pivotally secured arms having a plurality of notches provided on the bottom edges thereof.

DOMINICK KORYTAR.
